THOMAS BOOTH AND CHARLES CARROLL SANDERSON, OF NORWAY, MAINE.

Letters Patent No. 84,253, dated November 24, 1868.

IMPROVEMENT IN LET-OFF MECHANISM FOR LOOMS.

The Schedule referred to in these Letters Patent and making part of the same.

To all whom it may concern:

Be it known that we, THOMAS BOOTH and CHARLES CARROLL SANDERSON, both of Norway, in the county of Oxford, and State of Maine, have invented a new and useful Self-Adjusting Let-Off Mechanism for Looms; and we hereby declare the following to be a full, clear, and exact description thereof, which will enable others to make and use our invention, reference being had to the accompanying drawings, forming part of this specification, in which is shown a view of a loom-beam with our improvement thereto attached.

In the drawings, *a* shows the part of the loom into which is set the journal of the beam *b*.

The part *c* shows the size of the full beam.

b, the empty beam, or when there is no yarn thereon.

It is well known that when cloth is being manufactured, the weaver is directed to make the web with a certain number of picks to an inch, for instance, and in order to effect the even and regular density or closeness of the web throughout, two arms having weights are attached to the front of the loom, with bands passing over the beam, so as to regulate the speed of the delivery or unwinding of the yarns from the beam by the operation of the machine.

This method is not satisfactory, as it is not automatic, and is, moreover, liable to be tampered with by the operator, who, in the absence of the supervisor, can change the rapidity of the delivery of the yarns, and so diminish the number of picks to an inch, and, in consequence, the firmness, solidity, and uniformity of the web. When, as is usual, the operator is paid by the yard, this change is often made, in order to accomplish a larger amount of work within a day, or any given time.

Our invention seeks to place it within the power of the supervisor to arrange the delivery of the yarns so that they shall be uniform throughout the whole web, and to make this regulating-device automatic in operation, and so that it cannot be changed by the operator.

d shows a standard, attached to the cross-beam *e*, near the bottom of the loom. It has a pivot at *f*, upon which are hung the cross adjusting-arms *g g*. These arms can open or close, swinging on the said pivot.

Connected with *g g*, at *h h*, are the connecting-rods *i i*, which are also connected with the weights *j j*. These weights have holes, through which pass the arms *k k*, which are pivoted to the frame of the loom at *m m*. From these arms *k k* friction-bands pass up over the beam, or a truck thereon. (See *n n*.) At the lower end of the arms *g g* are adjusting-plates *o o*.

The operation is as follows:

As the beam revolves, and the yarns thereon wind off, the plates *o o* are all the time kept pressed up against the under side of the yarns wound around the beam, and are thus held by the operation of the weights, operating through links *i i* and pivoted arms *k k*. As the yarns are wound off, and the size of the beam is diminished, the weights *j j* slide downwardly on the smooth arms *k k*, and so on until the whole is wound off.

Now, when the beam is fullest, it is apparent that it must turn more slowly than when nearly empty, in order to deliver the yarns with equal speed under both circumstances. Therefore, when the web is first begun, the weights *j j* are up near the upper ends of the arms *k k*, making a greater leverage than when further down, and so pressing or binding the bands *n n* more tightly over the beam or its truck, and as the weights go down on the arms *k k*, the binding of *n n*, or their friction, is diminished in proportion as the cylinder from which the yarns are removed grows smaller in diameter; and thus the revolution of the beam *b* is somewhat accelerated, and the yarns always delivered uniformly. The result of this is apparent.

When the loom is gauged to a certain number of picks to the inch on the web, by means of the weights, the device is then self-adjusting, and the whole web is made of uniform closeness of texture.

Practice will readily determine the necessary weight of *j j* for different numbers of picks to the inch, and the length of arms *k k*, and these can be provided for all varieties of web.

Now, it will be seen that when once set to a certain number of picks to the inch on the web, the weaver has no power to change the standard, as with the old form, and thus accelerate the weaving and change the texture of the cloth.

It is apparent that a variety of forms of the levers *g g* can be employed, or a cam could be used instead of them, or gearing, but the principle of operation would be the same, the device being governed by the weights sliding on arms *k k*.

We do not limit ourselves to the exact device herein shown.

What we claim as our invention, and desire to secure by Letters Patent, is—

The combination of standard *d*, arms *g g*, rods *i i*, weights *j j*, arms *k k*, bands *n n*, with the beam *b*, as and for the purposes herein set forth.

THOMAS BOOTH.

CHARLES CARROLL SANDERSON.
